(57) **CLAIM**

The ornamental design for display screen or portion thereof with graphical user interface as shown and described.

DESCRIPTION

FIG. 1 is a front view of a display screen or portion thereof with graphical user interface according to a first embodiment of the present invention;

FIG. 2 is a front view of a display screen or portion thereof with graphical user interface according to a second embodiment of the present invention; and,

FIG. 3 is a front view of a display screen or portion thereof with graphical user interface according to a third embodiment of the present invention.

The broken line at the perimeter of the figures illustrates the display screen and the remaining broken lines illustrate portions of the graphical user interface. None of the broken lines form part of the claimed invention.

1 Claim, 3 Drawing Sheets
